HEAT EXCHANGERS OF THE ROTARY REGENERATOR TYPE

Walter S. Misener, Syracuse, N.Y., assignor to Carrier Corporation, Syracuse, N.Y., a corporation of Delaware

Application June 12, 1953, Serial No. 361,215

6 Claims. (Cl. 257—6)

This invention relates to regenerators and, more particularly, to regenerators in which the heat storage medium or matrix rotates about an axis traversing in turn two fluid streams flowing through the regenerator. The two streams are at different temperatures and at substantially different pressures. In this type of regenerator, a portion of the matrix passes through the warm gas duct and absorbs heat from the gas therein after which it passes adjacent a sealing means into the cold gas duct where it gives up heat to the gas therein, then passes adjacent a second sealing means or other portion of the first sealing means back into the warm gas duct to repeat the process.

The principal problems connected with this type of regenerator are those of leakage through the seal from the high pressure duct to the low pressure duct, and of carryover of gases trapped within the matrix, thus causing a net loss of gas from the high pressure duct. Loss of gas from the high pressure duct is caused by both of these phenomena; when this loss becomes excessive the value of the regenerator as an exchanger is impaired. In fact, to my knowledge, prior to the present invention, no satisfactory solution for these problems has been presented.

The present invention satisfactorily solves the problem while keeping other losses, such as pressure drop, within reasonable bounds by removing the seal from the regenerator matrix and reducing its perimeter to thereby reduce the leakage. Such procedure results in some additional volume between the seals within the rotor which is undesirable since it increases the carryover. However, with the present arrangement, the increase in carryover is less than the decrease in leakage so that an improvement in performance is obtained. The geometry for a minimum total of leakage and carryover may be defined in terms of the matrix and seal characteristics.

The chief object of this invention is to provide a regenerator having a matrix so formed that the combined total percentage of leakage and carryover is the minimum possible for any given set of matrix and seal characteristics.

A further object is to provide a stationary seal plate for a regenerator which will continuously seal against a rotating seal plate despite a varying pressure load tending to separate these two plates.

Another object is to provide a regenerator in which the matrix is formed of two, concentric, oppositely tapered, frusto-conical members or elements permitting axial flow into the matrix assembly, substantially radial flow through the matrix itself, and axial flow from the matrix assembly. Other objects of my invention will be readily perceived from the following description.

This invention relates to a regenerator comprising an annular housing, the housing having inner and outer concentric walls, a matrix member disposed in the housing, said member comprising two substantially frusto-conical elements extending in opposite directions about the axis of the housing, means dividing said elements into

2

separate portions, means for passing high pressure gases in contact with the matrix portions for a predetermined period and for passing low pressure gases in contact therewith for another period.

5 The attached drawings illustrate a preferred embodiment of my invention, in which:

Figure 1 is an isometric view of the whole matrix;

Figure 2 is a sectional view taken along the line II—II of Figure 1;

10 Figure 3 is a diagrammatic view of a portion of the regenerator showing details of the flow path;

Figure 4 is a sectional view of one embodiment of the regenerator;

Figure 5 is an end view partly in section and partly in elevation of the regenerator of Figure 4;

Figure 6 is an end view partly in section and partly in elevation of the regenerator taken in the opposite direction of Figure 5;

Figure 7 is a sectional view of a modification of the invention;

Figure 8 is a sectional view of the compensating means of the stationary sealing plate;

Figure 9 is a sectional view of a modification of the compensating means of the stationary sealing plate; and

25 Figure 10 is a sectional view of another modification of the compensating means of the stationary sealing plate.

The basic geometry of the present regenerator depends upon the use of two concentric frusto-conical matrices of opposite taper, as shown in Figure 1. This arrangement enables a relatively large matrix frontal area to be disposed between small flow entrance and exit areas, which results in small seal perimeters. The matrix frontal area is the area which is normal to the flow. This area is the surface area of the facing side of the two frusto-conical matrix elements. This arrangement, however, leaves space between the sealing planes within the rotor, which is not usefully occupied by the matrix which contributes to the carryover. The smaller the seal perimeter, the less will be leakage for any given quality of seal

30 (leakage per foot of seal length) and the larger will be the carryover for a regenerator of the preferred arrangement. This situation means that an optimum design exists in which for a given matrix design requiring a given amount of matrix frontal area and depth of matrix

35 and a given seal leakage per foot of length a specific geometry exists such that the total of leakage and carryover is a minimum. Figure 3 shows a cross section of a portion of the regenerator rotating housing on which

40 the basic dimensions are illustrated which define what is referred to as the regenerator geometry, and also what parameters and assumed dimensions are required to enable an optimum design to be obtained.

45 Here the major passage radius at the smaller opening (Figure 3) must be such that

55

$$R = \frac{W_a x + E/x}{2}$$

and the minor passage radius at the smaller opening (Figure 3) must be such that

60

$$r = \frac{W_a x - E/x}{2}$$

and the length of the matrix must be such that

65

$$l = D/x$$

70 in which case the total percentage of leakage and carryover is given by

75

$$\frac{A}{x} + Bx + C$$

where the magnitude of x is such that

$$.5x \leq \sqrt{\frac{A}{B}} < 1.5x$$

for best performance in which

$$A = \frac{5\rho'N \sin \theta \cos \theta}{6\pi(C_4 W_a / A f_a)^2} + \frac{400k_2 \sin \theta}{W_a \pi C_4 W_a / A f_a}$$

$$B = \frac{10\rho'N \pi L \Delta}{3} + 400k_1 C_4' \pi$$

$$C = \frac{5\rho'N}{3C_4 W_a / A f_a} (L \sin \theta + \Delta \cos \theta)$$

$$D = \frac{\cos \theta}{2\pi C_4 W_a / A f_a}$$

$$E = \frac{\sin \theta}{\pi C_4 W_a / A f_a}$$

and

$A f_a$ is matrix frontal area in high pressure region, ft.².
 C_4 is the fraction of the total annulus area within the high pressure region of the rotor.

C_4' is the fraction of the total annulus area within the high pressure ducting approaching the rotor.

k_1 is mean leak rate of circumferential portion of the seal, lbs./sec. ft.

k_2 is mean leak rate of the radial portion of the seal, lbs./sec. ft.

l is axial length of regenerator matrix, ft.

L is additional axial length of rotor inside seals, usually equal to matrix thickness, ft.

N is rotor revolutions per minute.

W_a is weight flow through high pressure region, lbs./sec.

θ is half cone angle of matrix, degrees.

ρ' is mean density difference (high pressure region minus low pressure region), lbs./ft.³.

Δ is distance from passage to inner and outer walls of rotor annulus.

It will be understood that the matrix, as previously described, must be incorporated within a housing and between sealing plates in order to serve its function as a heat transfer member. Means must also be provided for supplying gases of different temperatures to portions of the matrix members at different times. While the desired type of matrix member is that shown in Figure 1, it is desirable for commercial manufacture that these members 2 and 3 be divided into a plurality of portions circumferentially displaced from one another in order to limit the amount of carryover and assure effective heat transfer.

The particular type of regenerator, which I have found preferable, is shown in the drawings. Referring particularly to Figure 4, there is shown a casing 4. An annular housing 5 is located within the casing and spaced therefrom. This housing is adapted to be rotated and its particular operation will be described hereinafter. The housing is divided into a plurality of trapezoidal chambers 9. These chambers are provided by forming the housing of a series of separate boxes 6, which are trapezoidal in cross section. Each box contains a chamber 9. The details of the boxes will be described hereinafter.

It is obvious that the division of the housing into a plurality of chambers necessitates the division of the two matrix members 2 and 3 into a plurality of portions circumferentially displaced from one another. Each portion of the matrix member 2 is identified by the reference numeral 12, while each portion of the matrix member 3 is identified by the numeral 14. Each chamber 9 will contain a portion 12 and a portion 14, thus the portions 12 will make up the frusto-conical member 2, and the portions 14 will make up the frusto-conical member 3. The basic arrangement shown here, and in Figure 1, in which the matrix is arranged in the form of two frusto-conical members permits a very large matrix frontal area

or surface to be provided in a relatively small space. This permits the flow to be essentially radial through each portion 12 of member 2 and each portion 14 of member 3 and results in low pressure losses. The arrangement 5 also permits the flow to be essentially axial into and out of the matrix assembly so that a seal of small perimeter may be used.

Attached to each end of the annular housing 5 is a seal plate 15, which is adapted to rotate with the housing. 10 Each of these rotating seal plates has openings 16 that communicate with the chambers 9. These openings are of smaller size than the chambers to permit the mounting of the ends of the boxes 6 in the housing 5. If desired, one of the rotating seal plates may have openings of the 15 same size as the chamber.

The manner in which the regenerator may be formed is disclosed in the copending application of P. A. Weller, Serial No. 361,278, filed June 12, 1953. In the preferred

method of assembly, a series of discrete boxes 6 are 20 formed, each box containing a chamber 9. These boxes, which are trapezoidal in cross section, fit into grooves 17 formed in rotary seal plates 15. These grooves, of course, are of trapezoidal form. The seal plates 15 are held together against the boxes by a tie rod 18 and turn-buckle 19. While this method of assembly is preferred, it will be understood that other suitable means of assembly may be employed.

A stationary seal plate 22 is positioned adjacent one of the rotating seal plates. This stationary seal plate is 30 preferably circular to surround both the high pressure and low pressure passages with radial seals between the two, but it may be a sector of a circle and surround only the high pressure passage. This stationary seal plate 22 is affixed by means of a bellows 25 to the stationary structure or casing 4 which is connected to ducts 23 and 24. 35 Bellows 25 permits the stationary seal plate 22 to move with respect to the housing 5 and the casing 4.

At the other end of the housing there is located a second stationary seal plate 26. If desired, this plate 40 may be circular, but it preferably is only a sector of a circle surrounding high pressure duct 27 for a reason to be described hereinafter. This plate 26 is fastened to the casing 4 by a bellows 29 and hence it is fastened to the duct 27 since the duct is connected to the casing 4. Thus, 45 this stationary seal plate 26 is capable of moving with respect to the housing 5 and the casing 4.

High pressure gas flows from duct 27 to the housing, then flowing through the seal into the group of chambers 9, which happen to be opposite the high pressure duct 50 at that time, and out through the seal to duct 23. The low pressure gas flows from duct 24 to the housing, then passing through the applicable chambers 9 and leaves the housing, passing to the duct 28. While the flow of high pressure and low pressure gases is shown to be in opposite 55 directions and such an arrangement is preferred, it will be understood that the flow of gases could be in the same direction.

Since it does not matter if the low pressure gas leaks from the duct into the space between the housing and 60 the casing provided, of course, that it does not bypass the housing, only the high pressure passage need be sealed on either end of the regenerator. Means must be provided, however, to prevent the low pressure gas stream from bypassing the housing. This is accomplished, of course, when the stationary seal plate 22 is a complete circle. If the plate 22 is only a sector of a circle surrounding the high pressure passage, a seal must be provided at the inner and outer radii of one of the rotating seal plates 15.

70 Gear teeth 32 are shown on the periphery of the seal plate 15. These teeth mesh with gear teeth 33 of drive gear 34. This drive gear is connected by a shaft to a motor 35. While the housing is described as being rotated by rim drive, a shaft drive may be employed if desired. It also will be understood that suitable means

may be provided to rotate the ducts if desired, the housing remaining in a stationary position.

The stationary seal plates are composed of radial portions 40, an inner concentric portion 41, and an outer concentric portion 42. The area inside these portions defines the high pressure passage through the housing. In the event that one of the stationary seals is to enclose both the high and low pressure passages the concentric portions assume the shape of completely circular members instead of segments of a circle and it is preferable to join the inner and outer concentric portions by a small additional radial portion spanning what now becomes the low pressure passage.

It is obvious that as each chamber containing high pressure gas passes under one of the radial portions of a stationary seal plate that this particular radial portion will be subjected to a varying pressure, which will tend to lift the stationary plate away from the rotating plate and permit high pressure gases to leak into the low pressure sector. The rotation of the rotary seal plate with the housing causes the position of the actual line of sealing to move across the radial portion of the stationary seal plate, exposing varying parts of this portion to high and low pressures thereby causing a variable lifting force.

To assure sealing, it is desirable to apply a compensating force that is constant and equal to the maximum value of the lifting force or a compensating force that varies with the lifting force. I have found a practical solution using a compensating force that varies step-wise with the lifting force.

Each of the radial portions of the sealing plates is provided with a plurality of holes 50 that are spaced from one another. These holes are illustrated (see Figure 5) as being inclined with respect to each other, but they may be placed on the same circumference. Preferably, each of these holes (see Figure 8) is connected directly to a compensating bellows 44, which is connected to the sealing plate. This bellows is located in a cover 45 fastened to the casing 4. Disposed between the bellows and the cover is a ram 46. As the first pressure hole is exposed to the high pressure region, the compensating bellows connected to this hole picks up the same pressure. This results in the bellows attempting to expand towards the cover 45 but the ram 46 prevents this and the bellows expands towards the sealing plate. This causes the sealing plate to remain in the desired sealing position adjacent the rotary plate. As the second hole is exposed the second bellows takes effect. It is obvious that the number of bellows that can be used will depend on the particular desired results.

In the embodiment of Figure 9, the compensating bellows 44 is directly connected to the hole 50 and the sealing plate as in Figure 8. On the end of the bellows 44, there is provided a member 47 on which are hinged, at 47', two levers 48. Portions 48' of these levers extend therefrom to act on the sealing plate. Each of these levers 48 has a fulcrum, which is provided by the bolts 49 in the cover 45. These bolts are adjustable to prevent the bellows from being extended beyond the desired limit and to assure that the portions 48' will contact the seal plate when any pressure is applied through the hole 50 to bellows 44. As the hole 50 is exposed to the high pressure region, the compensating bellows picks up this pressure. This results in the bellows attempting to expand but its travel is limited. However, it does move sufficiently to cause the portions 48' to exert a force on the seal plate. Likewise, due to the limited travel of the bellows, there is a force exerted on the plate by the bellows. By applying the force at three points rather than one, it is obvious that the size of the bellows may be reduced accordingly. It will be understood that a plurality of these bellows will be connected to a plurality of holes as in Figure 8.

In the modification of Figure 10, each of the holes 50 is connected through a connecting tube 51 to the com-

pensating bellows 52. This bellows is located in a cover 53 fastened to the casing 4 and pushes against the seal by means of a ram 55. As the first pressure hole is exposed to the high pressure region, the compensating bellows connected to this hole picks up the same pressure and the ram 55 causes the sealing plate to be pushed against the rotating plate with an increased force. As the second hole is exposed the second ram is actuated. It is obvious that the number of bellows that can be used will depend on the particular desired results.

Considering the operation of the device, high temperature gases flow into the housing through the low pressure inlet duct 24. The portions 12 and 14 of the matrix members 2 and 3 absorb heat from this high temperature gas and store it therein until they pass through the low temperature gas being supplied by the high pressure duct 27. The high temperature gases, having been cooled by passing through the matrix, leave by duct 28. The low temperature gas entering through inlet duct 27 absorbs heat from the portion 12 and portion 14 of the matrix members 2 and 3 when they arrive opposite the high pressure stream. The movement of the portions of the matrix from one sector to another is accomplished by rotation of the housing 5 by the motor 35 through the drive gear 34.

It will be understood that the radial portions of the stationary seal plates have a greater circumferential width than any of the openings 16 in the rotary seal plate. This will prevent leakage from the high pressure side to the low pressure side. Carryover is, of course, determined by the volume of the chambers 9 and the speed of rotation.

Referring to the modification disclosed in Figure 7, there is shown a casing 60, preferably made of aluminum, and an annular housing 61 disposed within the casing 60 and spaced therefrom. This housing 61 is made up of a plurality of boxes 62 in the same manner as the housing 5 of Figure 4. Each of the boxes 62 contains a chamber 63 in which are disposed matrix portions 12 and 14 in the same manner as described with regard to Figure 4.

Attached to each end of the annular housing is a seal plate 64 that is adapted to rotate with the housing. Disposed between each seal plate and the end of the housing is a temperature equalizer member 65 made of copper or other material of high thermal conductivity. Stationary seal plate 67, connected by bellows 66 to the casing 60, is disposed adjacent one of the rotating seal plates. The second stationary seal plate 68, connected by bellows 69 to the casing 60, is disposed adjacent the other rotating seal plate. Each of these seal plates 67 and 68 forms only a sector of a circle to provide sealing about the high pressure sector in the same manner that sealing is accomplished by the seal plate 26 in the embodiment of Figure 4. Between the stationary plate 67 and the bellows 66 there is disposed a temperature equalizer member 70 made of copper or other material of high thermal conductivity. The member 70 forms only a sector of the circle. A member 71, similar to member 70, is disposed between the stationary seal plate 68 and bellows 69.

In the sector of the regenerator through which the low pressure gases pass there is disposed adjacent to each rotating seal plate a temperature equalizer member 72 made of copper or other high conductivity material. It will be understood that these members 72 are only a sector of a circle embracing that sector of the regenerator through which the low pressure gases pass.

Vanels 74 are disposed adjacent to the portions 12 and 14 of the matrix members 2 and 3. These vanes serve the purpose of guiding the gases radially through the portions 12 and 14. A divider 75 is disposed between the portions 12 and 14 to insure that the flow entering and leaving the chamber 63 is axial.

To insure that the low pressure gases will flow through

the chambers 63 and the matrix portion 12 and 14 rather than passing by means of the space between the members 72 and the rotary seal plate 64 through the space between the housing 61 and the casing 60, there is disposed a stationary sealing disk 76 adjacent to the inner edge of the rotating seal plate 64. A similar sealing disk 77 is disposed about the outer edge of the rotating seal plate 64. In the embodiment disclosed in Figure 7 the manner of flow and the heat transfer relation is the same as the embodiment of Figure 4 and an explanation of the operation of Figure 7 is not deemed necessary.

The present invention has the advantage of providing a regenerator with total leakage and carryover at a minimum even though the fluid pressures differ greatly. This particular minimum is obtained by a specific geometric pattern of the regenerator.

While I have described a preferred embodiment of my invention, it will be understood that my invention is not limited thereto since it may be otherwise embodied within the scope of the following claims.

I claim:

1. A regenerator comprising an annular housing, the housing having inner and outer concentric walls, a matrix member disposed in the housing, said member comprising two substantially frusto-conical elements extending in opposite directions about the axis of the housing, means dividing said elements into separate portions, means for passing high pressure gases in contact with the matrix portions for a predetermined period and for passing low pressure gases in contact therewith for another period.

2. A regenerator including an annular housing divided into a plurality of chambers, a matrix member disposed in the housing, said member comprising two substantially frusto-conical elements extending in opposite directions about the axis of the housing, portions of each element being placed in each chamber, means for passing high pressure gases in contact with each matrix portion for a predetermined period and for passing low pressure gases in contact therewith for another period.

3. A regenerator including an annular housing divided into a plurality of chambers, a matrix member disposed in the housing, said member comprising two substantially frusto-conical elements extending in opposite directions about the axis of the housing, portions of each element being placed in each chamber, and means automatically controlling the passage of both high pressure gases and low pressure gases to and from said chambers at regular time intervals.

4. A regenerator comprising an annular rotatable housing, said housing being divided into a plurality of chambers, a matrix member disposed in the housing about the axis of rotation, said member comprising two substantially frusto-conical elements extending in opposite directions about the axis of rotation, portions of each element being placed in each chamber, means in said housing to permit the flow of hot gases through one passage in communication with the matrix portions and to permit the flow of cool gases through another passage in communication with the matrix portions, the matrix portions absorbing heat during their communication with the hot gases and transferring this stored heat during their communication with the cool gases.

5. A regenerator comprising an annular housing, a matrix member disposed in the housing, said member comprising two substantially frusto-conical elements, said elements being inclined in opposite directions, one of said elements being disposed inside the other, said elements being coaxial with the axis of the housing, means dividing said elements into separate portions along substantially radial planes, means for passing high pressure gases through the annular housing and through the matrix portions therein, means for passing low pressure gases through the housing and through the matrix portions therein, and means for rotating the housing and the

matrix therein to permit the various portions of the matrix to pass in turn through the high pressure and low pressure gases.

6. A regenerator including an annular housing divided into a plurality of chambers, a matrix member disposed in the housing, said member comprising two substantially frusto-conical elements extending in opposite directions about the axis of the housing, portions of each element being placed in each chamber, the maximum inner radius of the outer frusto-conical element being equal to

$$\frac{W_a x + E/x}{2}$$

the minimum outer radius of the inner frusto-conical element being equal to

$$\frac{W_a x - E/x}{2}$$

and the length of each of the elements being equal to

$$\frac{D}{x}$$

where the magnitude of x is such that

$$.5x \leq \sqrt{\frac{A}{B}} < 1.5x$$

for best performance in which

$$A = \frac{5\rho'N \sin \theta \cos \theta}{6\pi(C_4 W_a / A f_a)^2} + \frac{400k_2 \sin \theta}{W_a \pi C_4 W_a / A f_a}$$

$$B = \frac{10\rho'N\pi L \Delta}{3} + 400k_1 C_4' \pi$$

$$D = \frac{\cos \theta}{2\pi C_4 W_a / A f_a}$$

$$E = \frac{\sin \theta}{\pi C_4 W_a / A f_a}$$

and

$A f_a$ is matrix frontal area in high pressure region, ft.².
 C_4 is the fraction of the total annulus area within the high pressure region of the rotor.

C_4' is the fraction of the total annulus area within the high pressure ducting approaching the rotor.

k_1 is mean leak rate of circumferential portion of the seal, lbs./sec. ft.

k_2 is mean leak rate of radial portion of seal, lbs./sec. ft.
 L is additional axial length of rotor inside seals, usually equal to matrix thickness, ft.

N is rotor revolutions per minute.

W_a is weight flow through high pressure region, lbs./sec.

θ is half cone angle of matrix, degrees.

ρ' is mean density difference (high pressure region minus low pressure region), lbs./ft.³.

Δ is distance from passage to inner and outer wall of

rotor annulus.
